BONE CONDUCTION RECEIVER

Samuel F. Lybarger, Mount Lebanon, Pa., assignor to E. A. Myers & Sons, Mount Lebanon, Pa., a partnership consisting of Edward A. Myers, Edwin J. Myers, Alfred E. Pelz, and Samuel F. Lybarger

Application October 5, 1938, Serial No. 233,343

16 Claims. (CL 179—107)

This invention relates to hearing-aid receivers for hard-of-hearing people, and more particularly to bone conduction receivers of the direct action type.

5 There are two general types of bone conduction receivers. In the indirect or inertia reaction type of vibratory member is directly supported by a head-band or other means against a hearing inducing bone of the user where it is

10 vibrated by reaction forces generated by a floating electromagnetic body supported by the vibratory member. In the direct action type the electromagnetic means is directly supported by the head-band and in turn supports the vibratory member against the hearing inducing bone. This latter type of receiver is sometimes referred to as the button type because the vibratory member often resembles a button vibrated by the electromagnetic means.

15

20 In the inertia reaction-type receiver it is immaterial so far as the air gap between the vibratory member and electromagnetic means is concerned, as to how much pressure is applied to the vibratory member by the head-band, because the

25 band is connected directly to the vibratory member and therefore this pressure cannot decrease the width of the air gap. On the other hand, a serious objection to direct action receivers known heretofore has been that the pressure of the

30 head-band against the electromagnetic means forces it toward the vibratory member and thereby decreases the air gap. Attempts to overcome this difficulty by initially making the air gap greater than it should be so that it will be

35 decreased to the correct width when the receiver is in position generally have not been successful because the pressure applied to the receiver by its supporting means varies with different individuals, due to distortion of the supporting means, or to differences in the shape of heads.

40 Although the problem may be solved to some extent by stiffening the resilient support for the vibratory member so that it will offer greater resistance to closing of the gap, this brings about

45 other disadvantages, such as impairment of response characteristics, especially in the low frequency band.

The importance of minimizing or eliminating the effect of the head-band pressure on the air gap will be more evident when the following facts are considered. Head-band pressure generally varies with different individuals from about 5 to 15 ounces, a desirable air gap is of the order of .003" (.0075 cm.), and the stiffness of the spring system within most receivers as measured at the

air gap should be of the order of 30 to 100×10^6 dynes per cm. if efficient operation is to be obtained. If, for example, this stiffness is 80×10^6 dynes per cm., a change in head-band pressure of one ounce (27,800 dynes) will cause a change of

$$\frac{27800}{80 \times 10^6} = 0.00035 \text{ cm.}$$

in the air gap spacing. A change of 10 oz. in pressure would cause a change of .0035 cm., or almost half of the desirable air gap spacing.

In prior types of receivers the effective mass of the head-band yoke is added directly to the effective mass of the receiver case because the yoke is attached to the case at a point where the amplitude of vibration is substantially greatest. The resulting total effective mass is often too great to permit of the desired frequency response characteristics in the middle frequency range.

Consequently, direct action bone conduction receivers have never been very satisfactory heretofore when held in position by a head-band or the like.

It is among the objects of this invention to provide a direct action bone conduction receiver for hearing aids and the like in which the tendency of the pressure of its supporting means to affect the spacing of its air gap is greatly decreased, and can be eliminated entirely if desired, without impairing the desired response characteristics. Another object is to provide a closed housing for the electromagnetic system of the receiver in which the vibratory member forms one wall of the housing.

In accordance with this invention a substantially rigid vibratory member adapted to be pressed against a hearing inducing bone of the hard-of-hearing person, such as the mastoid bone, is disposed adjacent one end of the pole-piece of an electromagnet with an air gap between them. The means that connects the opposite end of the pole-piece to the vibratory member and thereby supports it has a resilient portion spaced laterally from the air gap. The vibratory member is held in operative position by suitable supporting means, such as a head-band, irresiliently connected with the pole-piece so that the pole-piece can not vibrate relative to its support. The pressure by which the supporting means presses the vibratory member toward the bone is applied to the receiver at a point between its air gap and the above-mentioned resilient portion whereby the effect of this pressure on the width of the air gap is decreased. By providing

the means that connects the vibratory member to the pole-piece with two laterally spaced resilient portions at one side of the air gap, and attaching the supporting means to the receiver at a point between these two resilient portions, the tendency of the supporting pressure to alter the air gap can be controlled to the point of elimination. This desirable result is obtained without impairing in any noticeable way the response characteristics of the receiver. Preferably, the vibratory member itself forms a cover for the case that houses the electromagnetic means. As the vibratory member must be spaced from the side walls of the case in order to vibrate relative thereto, the intervening space is sealed by a highly resilient gasket to keep out dust and dirt.

The invention is illustrated in the accompanying drawings in which Fig. 1 is a side view of my receiver as applied to the head behind an ear; Fig. 2 is an enlarged plan view of the receiver as seen when it is lying with its vibratory member face down; Fig. 3 is a longitudinal section taken on the line III—III of Fig. 2; Fig. 4 is a transverse section taken on the line IV—IV of Fig. 2; Fig. 5 is a diagrammatic illustration of the foregoing receiver; Figs. 6, 7 and 8 are views similar to Fig. 3 of three modified embodiments of this invention; and Fig. 9 is a plan view of the receiver of Fig. 8 minus its case.

As viewed in Figs. 2 to 4 of the drawings, an integral case 1, which is generally rectangular in cross section, has a top and depending side and end walls and an open bottom. Mounted in this case is electromagnetic means for driving a vibratory member in accordance with variations in electric current caused by a microphone responding to sound waves. The electromagnetic means or system includes a permanent bar magnet 2 to one end of which is secured a metal pole-piece 3 that has a portion extending substantially at right angles to the magnet and towards the open bottom of the case. The inner end of the pole-piece is preferably disposed between the magnet, to which it is connected by screws 4, and the top of the case. The pole-piece and magnet are rigidly attached to the top of the case by screws 5 threaded into the pole-piece, and by screws 6 connected to a spacer member 8 between the opposite end of the case and the magnet to which the spacer member is attached by screws 9. The outwardly projecting portion of the pole-piece is encircled by an electromagnetic coil 11 connected by wires 12 to metal spring strips 13 secured at one end to the sides of the case with their other ends projecting partway across a pair of openings 14 through the adjoining end wall of the case. These openings are adapted to receive electric plugs 16 that engage springs 13 and connect them with the microphone or amplifier unit (not shown) of the hearing-aid system.

Extending across the open bottom of the case and forming a cover therefor is a rigid plate-like button or vibratory member 17 adapted to engage a hearing inducing bone, such as the mastoid bone, of a hard-of-hearing person. Of course, engagement with a bone means contact with the skin overlying the bone. This vibratory member is supported from the interior of the case in predetermined spaced relation with the outer end of the pole-piece by means of an elongate member 18 which is resilient wholly or in part to permit the vibratory member to be vibrated by the electromagnet. As the vibratory member is rigid, it must also be spaced a slight

distance from case 1 so that its movements will not be prevented by the case. This space is closed by a highly resilient gasket 19 of felt, rubber, sponge rubber, or the like that seals out dust and dirt without impairing the operation of the receiver. Being a direct action-type receiver, the vibratory member is pressed against the head or other bone structure by the case through elongate member 18, the case being directly supported by suitable means, such as a head-band.

As shown in Figs. 1 and 2, the band includes a curved strip 20 of spring metal adapted to fit over the head, and a yoke 21 pivotally connected to the metal strip and straddling the case. The ends of the yoke are provided with pins 22 that are pivotally mounted in holes 23 in the opposite sides of the case so that the case can tilt vertically relative to the yoke to better adjust itself to the contour of the head. The outer surface of the vibratory member is preferably curved longitudinally to give a greater area of contact with the head so as to rest more comfortably against it, and also to better retain the vibratory member in position.

It is a feature of this invention that this receiver is so constructed that it can be supported by the head-band or other supporting means in such manner that the pressure by which the latter presses the vibratory member against the bone structure does not appreciably vary the spacing of the air gap 26 between the vibratory member and pole-piece. Accordingly, elongate member 18 is connected to the vibratory member adjacent the pole-piece by screws 27, and extends away from both of them toward the opposite end of the case to which it is connected either directly or indirectly. Preferably, this inner end of the elongate member is connected to magnet bar 2 at the end opposite to the pole-piece by screws 9. Also, the end portions of the elongate member are offset whereby its straight central portion is spaced from both the vibratory member and the magnet bar. By making elongate member 18 of magnetic metal, its outer end can serve as the armature for the electromagnetic system when extended across the end of the pole-piece as shown in Fig. 3. In spite of the pole-piece being rigidly mounted in the case, it can be sprung away from magnet 2 a very slight amount by set screw 28 to increase the width of air gap 26.

Even though the elongate member is resilient throughout its length, most of its bending during vibration of the vibratory member occurs near its inner end because the leverage exerted at that point is greater than at any other point. For the same reason the elongate member bends adjacent its outer end in case the head-band pressure forces its inner end toward the vibratory member. As it is desirable for the purposes of this invention that such bending of the elongate member be more or less localized at two longitudinally spaced points in this manner, its straight central portion is preferably provided with longitudinally extending corrugations 29 to stiffen it so that it will not bend appreciably. Nevertheless, wherever it states herein that the elongate member is provided with longitudinally spaced resilient portions, it is to be understood, unless the contrary is stated, that the intermediate portion may also be resilient but that the major or entire amount of the bending of the elongate member occurs substantially only at the spaced resilient points for the reasons given above.

Fig. 5 is a diagrammatic representation of Fig. 3 for the purpose of more clearly illustrating my invention by showing the reaction of the receiver to the head-band when it presses the receiver against the head. Line 3 represents the pole-piece, line 2 the bar magnet, line 17 the vibratory member, line 18 the connecting elongate member, and dots J and K the resilient end portions or springs of the elongate member. It will be seen from Fig. 5 that if the head-band were attached to the receiver at a point where it would exert pressure in the upper end of pole-piece 3 directly above air gap 26, it would tend to push the pole-piece toward the vibratory member. However, if, in accordance with this invention, the same head-band pressure P acts on magnet 2 at the right of the pole-piece, it will have considerably less effect on the air gap spacing because the length of the lever arm between the point of pressure application and spring J is shortened and therefore the pressure can not flex the spring so easily. As most of the springing during vibration occurs at J, the amplitude of vibration of the vibratory member is greatest at the farther end, adjacent the air gap. Therefore, it is desirable to maintain good contact between the left end of the vibratory member and the head, and so the point of head-band pressure should not be too far to the right of the pole-piece.

It will be seen from Fig. 5 that when the head-band pressure acts on magnet 2 at a point between springs J and K, the tendency of that pressure to push the pole-piece toward the left end of the vibratory member is offset or counteracted by the tendency of the reaction P' to that force to push the right end of the vibratory member toward the right end of the magnet. The result is that the air gap remains more or less constant. The point of pressure application at which any tendency of the pressure to affect the air gap is eliminated can be determined. This depends on the relation of the length of line 2 to the length of line 17 between the air gap and spring K, and the relation of the resiliency of spring J to that of K. The resiliency of K can be less than J without materially affecting the vibration characteristics of the instrument because most of the vibrational springing occurs at J:

In the modification disclosed in Fig. 6, the vibratory member 17 is supported from permanent magnet 2 in the same general manner as the previously described embodiment. However, in this case the elongate supporting means is made in two parts that are overlapped and fastened together by screws 31. The inner member 32 has a straight portion and an offset end secured to the magnet by screws 9. The outer member 33 is straight from end to end and is secured to the vibratory member opposite the pole-piece by screws 34. Bending of these two members can be concentrated at longitudinally spaced points by providing each of them with a transverse notch or groove 36. The grooves must not be so deep that any appreciable effect on the magnetic flux is introduced because of magnetic saturation at these points. The grooves are also useful as a means of adjusting the values of the effective stiffness of the members at the grooves. Of course, the overlapping portions of these members make the central portion of the elongate supporting means rigid.

To permit relative movement of the vibratory member and stiff central portion of the elongate

means toward and away from each other so that pressure of the head against the vibratory member will compensate for the pressure of the head-band on the case, as far as the air gap is concerned, member 33 is spaced from the vibratory member by a spacing washer 37 at its fixed end. The spacing of the air gap can be adjusted by means of a set screw 38 to which access can be gained at any time through an opening 39 in the vibratory member which is normally closed by a plug 40. This two-piece supporting member permits separate testing and adjustment of members 32 and 33 before assembly in a somewhat easier manner than possible with a one-piece spring.

Fig. 7 illustrates a receiver of this character in which the means for supporting the vibratory member consists of a one-piece elongate member or spring 41. The inner end of the spring is offset and rigidly connected to permanent magnet 2, but the remaining portion of the spring is straight. This straight portion extends parallel to the vibratory member to which it is connected by screws 42 between the air gap and its opposite end, and may extend beyond this point of attachment so as to form an armature beneath the pole-piece. This extension should be short enough to act substantially as a rigid member. The spring is spaced from the vibratory member by a spacing washer 43 to permit movement of the spring and vibratory member relative to each other as previously described. If desired, this spring may be provided with grooves to concentrate bending at longitudinally spaced points, but it will work satisfactorily without notches because the distribution of the bending moment stresses in it is such as to provide, in effect, a division of the bending of the spring into two longitudinally spaced portions as is the case with spring 18 shown in Fig. 3. Attachment of the spring to the vibratory member at the right of the air gap has some advantage in that the attachment point is nearer the center of the receiver.

A further modification of the invention is shown in Figs. 8 and 9 in which the supporting spring member 51 is in no way associated with the magnetic circuit of the receiver. This makes it possible for a non-magnetic spring to be used, and also permits the use of steels which have good mechanical properties but whose magnetic properties are poor. In this embodiment a compact bipolar electromagnet is formed from a permanent magnet 52 having at its opposite sides depending pole-pieces 53 carrying coils 54. The pole-pieces are connected to the magnet by non-magnetic screws 56 passing therethrough and also through the forwardly projecting arms of a bracket 57 by which the electromagnet is attached to the inner end of the substantially U-shaped spring 51. The inner leg of the spring is rigidly secured to the top of the case by screws 58, while its outer leg is spaced from the vibratory member by means of a washer 59 beneath the magnet at which point the spring is secured to the vibratory member by screws 60. These screws also connect an armature 62 of good magnetic material to the end of the spring to complete the magnetic circuit of the receiver. The spring may be provided in its outer leg and in its intermediate portion with grooves 63 and 64 to concentrate its bending at those two points.

Fig. 8 also illustrates the use of another type of gasket for sealing the space between the case and vibratory member. This gasket 66, instead of being solid, is U-shape in cross section with 75

one leg engaging the case and the other engaging the vibratory member. Such a gasket is highly resilient because it can open and close with the vibrations of the receiver.

5 It will thus be understood that in a receiver made in accordance with this invention the tendency of the head-band pressure to alter the air gap can be reduced so that it is no longer objectionable, or it can be eliminated entirely. Another advantage, especially where it is desirable to increase response in the middle frequency range, resulting from the same construction is that the effect of the added mass of the head-band yoke is minimized because the head-band 10 is attached to the receiver at a point where the amplitude of vibration of the case is relatively small. By merely attaching the head-band to the vibratory member instead of to the case, and placing the case against the head, the effective vibratory mass can be still further reduced in order to increase response in the middle frequency 15 range.

According to the provisions of the patent statutes I have explained the principle and mode of operation of my invention and have illustrated and described what I now consider to represent its best embodiment. However, I desire to have it understood that, within the scope of the appended claims, the invention may be practiced 20 otherwise than as specifically illustrated and described.

I claim:

1. A direct action bone conduction receiver comprising a pole-piece, a vibratory member adjacent the pole-piece, elongate means connected at one end to the vibratory member adjacent the pole-piece and extending away from both of them, and rigid means connecting the pole-piece and the opposite end of the elongate means, said elongate means having longitudinally spaced resilient portions, the receiver being formed for connection to supporting means that applies pressure to said rigid means at a location between said resilient portions for holding the vibratory member against a hearing inducing bone of the user.

2. A direct action bone conduction receiver adapted to be supported by a head-band or the like, comprising a pole-piece, a plate-like vibratory member adjacent the pole-piece, a resilient member connected only to the end of the vibratory member adjacent the pole-piece and extending away from both of them, and rigid means connecting the pole-piece and the far end of the resilient member, said rigid means having a portion located between the ends of the resilient member for connection to the head-band.

3. The combination with a resilient head-band for supporting a hearing-aid receiver against the head of the user, of a direct action bone conduction receiver comprising a pole-piece, a vibratory member adjacent the pole-piece, elongate means connected at one end to the vibratory member adjacent the pole-piece and extending away from both of them, and rigid means connecting the pole-piece and the opposite end of the elongate means, said elongate means being provided with longitudinally spaced transverse grooves to form spaced resilient areas, the head-band being connected to said rigid means at a location between the resilient areas of said elongate means for pressing the vibratory member against a hearing inducing bone of the user.

4. A direct action bone conduction receiver comprising a pole-piece, a vibratory member ad-

jacent the pole-piece, elongate means connected at one end to the vibratory member adjacent the pole-piece and extending laterally therefrom, means spacing said end of the elongate means from the vibratory member, the opposite end 5 of said elongate means being offset from the vibratory member, and rigid means connecting the pole-piece and said offset end of the elongate means, said elongate means having longitudinally spaced resilient portions between said ends, the receiver being formed for connection to supporting means that applies pressure to said rigid means at a location between said resilient portions for holding the vibratory member against a hearing inducing bone of the user.

5. A direct action bone conduction receiver comprising a pole-piece, a vibratory member adjacent the pole-piece, elongate means connected at one end to the vibratory member adjacent the pole-piece and having a substantially straight 20 portion extending laterally therefrom, spacing means disposed between only said end of the elongate means and the vibratory member, the opposite end of said elongate means being offset from the vibratory member, and rigid means connecting the pole-piece and said offset end of the elongate means, said elongate means having longitudinally spaced resilient portions between said ends, the receiver being formed for connection to supporting means that applies pressure to said rigid means at a location between said resilient portions for holding the vibratory member against a hearing inducing bone of the user.

6. A direct action bone conduction receiver comprising a pole-piece, a vibratory member adjacent the pole-piece, elongate means having a substantially straight portion extending along the vibratory member away from the pole-piece, means at one side of the pole-piece for spacing said elongate means from the vibratory member, 40 means for connecting said elongate means and spacing means to the vibratory member, the opposite end of said elongate means being offset from the vibratory member, and rigid means connecting the pole-piece and said offset end of the 45 elongate means, said elongate means being resilient and adapted to flex principally in two longitudinally spaced portions between said ends, the receiver being formed for connection to supporting means that applies pressure to said rigid 50 means at a location between said longitudinally spaced portions for holding the vibratory member against a hearing inducing bone of the user.

7. A direct action bone conduction receiver comprising a pole-piece, a vibratory member adjacent the pole-piece, elongate means connected at one end to the vibratory member adjacent the pole-piece and extending away from both of them, rigid means connecting the pole-piece and the opposite end of the elongate means, said elongate 60 means having longitudinally spaced resilient portions, and including overlapping members, means for connecting them together, and means for springing them apart a slight amount to vary the spacing of the air gap, the receiver being 65 formed for connection to supporting means that applies pressure to said rigid means at a location between said resilient portions for holding the vibratory member against a hearing inducing bone of the user.

8. A direct action bone conduction receiver comprising a pole-piece, a vibratory member adjacent the pole-piece with an air gap between them, a substantially U-shape member having a leg extending substantially parallel to the vi- 75

bratory member in spaced relation thereto with its end connected to the vibratory member adjacent one end of the pole-piece, the end of the opposite leg being connected to the pole-piece, said U-shape member having longitudinally spaced resilient portions, the receiver being formed for connection to supporting means that applies pressure to said opposite leg of the U-shape member at a location between said resilient portions for holding the vibratory member against a hearing inducing bone of the user.

9. In combination, a direct action bone conduction receiver comprising a pole-piece, a vibratory member adjacent the pole-piece, elongate means connected at one end to the vibratory member adjacent the pole-piece and having a portion extending between them and forming an armature spaced from the pole-piece, the remainder of said means being spaced from the vibratory member, rigid means connecting the pole-piece and the opposite end of the elongate means, said elongate means having longitudinally spaced resilient portions, and supporting means connected to the receiver at a location between said resilient portions of the elongate means for applying pressure to said rigid means to hold the vibratory member against a hearing inducing bone of the user.

10. In combination, a direct action bone conduction receiver comprising a pole-piece, a vibratory member adjacent the pole-piece, elongate means connected at one end to the vibratory member adjacent the pole-piece and extending away from both of them, rigid means connecting the pole-piece and the opposite end of the elongate means, said elongate means having longitudinally spaced resilient portions, and supporting means adapted to apply pressure to said rigid means at a location substantially midway between said resilient portions for holding the vibratory member against a hearing inducing bone of the user.

11. In combination, a direct action bone conduction receiver comprising a pole-piece, a vibratory member adjacent the pole-piece, elongate means connected at one end to the vibratory member adjacent the pole-piece and extending away from both of them, rigid means connecting the pole-piece and the opposite end of the elongate means, said elongate means having longitudinally spaced resilient portions, and means for supporting the receiver adjacent a hearing inducing bone of the user and for pressing the vibratory member toward the bone, said supporting means being connected to said rigid means substantially at the location between said resilient portions of the elongate means at which the tendency of the pressure of the supporting means to force the pole-piece closer to the vibratory member is substantially counteracted by the tendency of the reaction to that pressure to spread them farther apart.

12. A direct action bone conduction receiver comprising a vibratory member, a permanent bar magnet spaced therefrom substantially parallel thereto, a pole-piece connected to one end of the magnet and extending toward the vibratory member, an elongate member having resilient end portions rigidly connected to the opposite end of the magnet and to the vibratory member adjacent the pole-piece, the receiver being formed for irresiliently connecting the magnet and pole-piece to means for holding the vibratory member against a hearing inducing bone of the user with pressure applied to the magnet at

a location between the resilient ends of the elongate member.

13. A direct action bone conduction receiver comprising a case open at one side, electromagnetic means rigidly mounted in one end of the case, a resilient member rigidly connected to the other end of the case and extending freely toward said one end and the open side of the case, and a rigid vibratory member extending across the open side of the case and having only its end adjacent said electromagnetic means rigidly mounted on the outer end portion of said resilient member, the case being formed for attachment to means for supporting it adjacent a hearing inducing bone of the user and for pressing the vibratory member toward the bone with a pressure applied to the case at a location between the ends of the resilient member, whereby the effect of said pressure on the spacing of the air gap is reduced.

14. A direct action bone conduction receiver comprising a case open at one side, electromagnetic means rigidly mounted in one end of the case, a resilient member rigidly connected to the other end of the case and extending diagonally toward said electromagnetic means and the open side of the case, a rigid vibratory member extending across the open side of the case and rigidly mounted on the outer end portion of said resilient member only at a location adjacent said electromagnetic means, and a highly resilient gasket disposed between the vibratory member and the wall of the case surrounding its open side for sealing the space between them, the case being formed for attachment to means for supporting it adjacent a hearing inducing bone of the user and for pressing the vibratory member toward the bone with a pressure applied to the case at a location between the ends of the resilient member, whereby the effect of said pressure on the spacing of the air gap is reduced.

15. In combination, a case open at one side, electromagnetic means rigidly mounted in one end of the case, a resilient member rigidly connected to the other end of the case and extending freely toward said one end and the open side of the case, and a rigid vibratory member extending across the open side of the case and rigidly mounted on the outer end portion of said resilient member only at a location adjacent said electromagnetic means, the case being provided in its sides with a pair of oppositely disposed openings located between the ends of the resilient member, and a head-band having a yoke with inwardly projecting pins that extend into said openings.

16. In combination, a case open at one side, electromagnetic means rigidly mounted in one end of the case, a resilient member rigidly connected to the other end of the case and extending freely toward said one end and the open side of the case, said member having more resiliency in two longitudinally spaced portions than elsewhere, and a rigid vibratory member extending across the open side of the case and rigidly mounted on the outer end portion of said resilient member, the case being provided in its sides with a pair of oppositely disposed openings located between the ends of the resilient member substantially midway between its most resilient portions, and a head-band having a yoke with inwardly projecting pins that extend into said openings.
